UNITED STATES PATENT OFFICE.

THOMAS S. PERKINS, OF WILKINSBURG, PENNSYLVANIA, ASSIGNOR TO
WESTINGHOUSE ELECTRIC & MANUFACTURING COMPANY, A CORPORA-
TION OF PENNSYLVANIA.

RHEOSTAT.

SPECIFICATION forming part of Letters Patent No. 740,175, dated September 29, 1903.

Application filed November 13, 1902. Serial No. 131,134. (No model.)

To all whom it may concern:

Be it known that I, THOMAS S. PERKINS, a citizen of the United States, residing in Wilkinsburg, in the county of Allegheny and State of Pennsylvania, have invented a new and useful Improvement in Rheostats, of which the following is a specification.

My invention relates to apparatus employed in connection with the operation of electrical machines for varying the currents generated thereby or supplied thereto; and it has for its object to provide a rheostat element or resistance-box of simple and inexpensive construction and one which may be readily assembled, thoroughly ventilated, and be efficient and durable in use.

In the operation of electric motors, notably those employed for driving railway-vehicles, the large and frequent variations in speed and the prevention of rushes of current in starting ordinarily necessitate the employment of considerable ohmic resistance, which is cut into and out of circuit in accordance with the exigencies of the service.

In order that the amount of resistance may be varied over a considerable range, several elements are usually employed, which are preferably of like construction and are cut into and out of circuit by means of a suitable controlling-switch. My present invention is well adapted to this service, but may also be utilized in any relation where ohmic resistance is needed.

My invention is illustrated in the accompanying drawings, in which—

Figure 1 is a side elevation of a resistance box or structure, a portion of the same being broken away. Fig. 2 is a plan view, and Fig. 3 is an end elevation, of the apparatus shown in Fig. 1.

The resistance portion of the box or structure 1 consists of a set of grids 2 of zigzag formation and for convenience and cheapness of construction will generally be of iron and cast in suitable molds. These grids may be otherwise formed and may be made of other material than iron, if desired; but on account of cheapness of material and facility of manufacture cast-iron is preferred.

Each end of each grid terminates in a limb

3 of a little more than half the length of the intermediate portions and of considerably greater cross-section. This limb terminates in a hollow boss 4, having a lug or projection 5, the outer face of which may be a plain surface for the purpose of receiving a connecting plate or strip 6. Adjacent projections 5 are joined by means of the strips or plates 6, and screws 7, the strips or plates being of such length as to connect the grids in circuit in the desired order. As indicated in the drawings, the grids are all connected in series; but obviously the plates may be of such dimensions as to connect the grids either all in multiple or in such multiple-series arrangement as may be found desirable. Each set of grids formed by the connecting strips or plates 6 is separated from the adjacent set by insulating-washers 8. The sets of grids thus arranged and combined may be connected in circuit by means of terminal posts 9, which may be screwed into any two of the projections 5 in lieu of the screws 7. If the grids are all to be connected in circuit, the posts will be mounted upon the projections 5 of the end grids, as indicated in Figs. 1 and 2 of the drawings.

In order to support the parts thus far described, I provide two end plates 10, here shown as of open-work construction in order to promote ventilation and also to lighten the structure, and I connect these end plates by means of two bolts 11 at the top, two similar bolts 12 at the bottom, and two bolts 13 at each side and substantially midway between the top and bottom, the latter extending through the hollow bosses 4 and the washers 8 and being surrounded by insulating-tubes 14, so as to insure electrical connection of the grids in the desired relation in the circuit. The connecting strips or plates 6 are preferably formed of copper or other good conducting material, so as to insure good electrical connection between adjacent grids, notwithstanding rough treatment, exposure to the weather, or expansion and contraction by reason of heating and cooling, which may tend to produce imperfect contact between the meeting sides of the bosses.

The structure shown and described and

constituting my invention may be supported by means of plates or bars 15, which are bolted to the end plates 10, as shown in the drawings, and the entire structure, as will be readily seen, is as light as the nature of the materials employed will permit, is thoroughly ventilated, tends to eliminate objectionable vibration and strains, and is simple and inexpensive in construction.

10 The form and dimensions of the structure as a whole and of the constituent parts may of course be varied from what is shown without departing from my invention.

I claim as my invention—

15 1. An electrical resistance structure comprising a frame, a set of grids of zigzag formation clamped therein and provided with end bosses having plane surfaces perpendicular to the planes of the grids, and strips or plates of relatively good conductivity fastened to the said plane surfaces of adjacent bosses.

20 2. An electrical resistance structure comprising a frame, a set of cast-iron grids of zigzag formation severally provided with bosses at their ends having plane surfaces perpendicular to the planes of the grids, strips or plates of relatively high conductivity fastened to the said plane surfaces of adjacent bosses so as to connect the grids in the desired relation and insulating-washers between the sets of bosses so connected.

25 3. An electrical resistance structure comprising a frame, a set of cast-metal grids of zigzag formation severally provided with end bosses having plane surfaces perpendicular to the planes of the grids, insulating-washers so disposed between the bosses as to connect the grids in series and plates or strips of relatively good conductivity closely fitted and fastened to the said plane surfaces of the several sets of bosses that are included between adjacent washers.

40 4. An electrical resistance structure comprising a set of cast-metal grids of zigzag formation provided with hollow bosses at their ends having plane surfaces perpendicular to

the planes of the grids, plates of relatively good conductivity so fastened to said plane surfaces as to connect the grids in circuit in the desired manner, insulating-washers for separating the sets of bosses and a frame consisting of end plates and connecting-bolts two of which extend through the sets of bosses and insulating-washers. 5

5. An electrical resistance structure comprising a set of grids of zigzag formation each of which has end limbs of relatively large cross-section and terminating in bosses having plane surfaces perpendicular to the 6 planes of the grids, and connecting-strips fastened to said plane surfaces.

6. An electrical resistance structure comprising a plurality of grids of zigzag formation each of which has short end limbs of relatively large cross-section and terminating in perforated bosses having plane surfaces perpendicular to the planes of the grids, metal strips fastened to said plane surfaces to connect said bosses in the desired relation, 7 end plates, rods which extend through the grid-bosses and plates and nuts coöperating with said plates and rods to clamp the grids together.

7. An electrical resistance structure consisting of a plurality of grids of zigzag formation, each of which has short end limbs of relatively large cross-section and terminating in perforated bosses having plane surfaces perpendicular to the planes of the grids, 8 metal strips fastened to said plane surfaces to connect said bosses in the desired electrical relation and a frame comprising end plates and bolts or rods two of which extend through the grid-bosses and are insulated 8 therefrom.

In testimony whereof I have hereunto subscribed my name this 31st day of October, 1902.

THOMAS S. PERKINS.
